UNITED STATES PATENT OFFICE.

THOMAS JAMES PRIESTMAN, OF BIRMINGHAM, ENGLAND.

PAVING BLOCK.

Application filed November 13, 1926, Serial No. 148,287, and in Great Britain October 12, 1925.

This invention relates to blocks for the purpose of forming traffic control lines in the roadway.

The object of the present invention is to provide improved means for forming the traffic control lines in roadways and it incorporates either metal plates having means whereby they may be anchored in the material (when in a plastic state) of which the road is made, or (preferably) complete blocks consisting of the metal plates permanently secured to blocks of concrete or like material.

According to the present invention I provide a traffic control line element comprising a metal plate having upon its under surface a number of downwardly extending integrally formed bosses or lugs, within each of which is embedded the head of an anchor member with the projecting portion of which the cement, concrete or other block or foundation is adapted to engage.

These prongs preferably consist of rods or bifurcated rivets having suitable heads for engaging in the lugs, the prongs being secured within the lugs by being cast therein.

The prongs may consist of lengths of wire or rod bent at the centre to form an eye, this eye being embedded in the boss or lug upon the metal plate, the metal of the boss or lug passing through the eye.

Before attaching such plates by embedding the prongs in the concrete or foundation, the bifurcated rivets may have their sides opened out or moved apart so as to engage more effectively with the block or foundation.

Each of my paving blocks may conveniently form a letter or indicator, such as an arrow, whilst a series of blocks may form any suitable combination of letters such as the letters S T O P. These letters may be conveniently formed by providing the metallic element with an opening corresponding to the shape of letter required, this opening being filled by means of any suitable material. This may consist of a suitably coloured cement which will produce a non-slipping surface, and at the same time will be readily seen against the surrounding roadway, or if desired the filling material may be formed by the concrete or the like forming the roadway and be forced upwardly into the opening in the metallic element when it is mounted in position.

The openings formed in the plates may be filled if desired by means of blocks of rubber or other similar material, and these blocks may be provided with flanges or the like to retain them securely in position.

In any case the plates may be mounted upon concrete or like blocks so as to form bricks, and the spaces around the arrow or other device may be filled in on the surface of the concrete or the like with any suitable composition, preferably of a dark colour so as to cause the arrow or other indicating or signalling device to show up clearly.

Referring to the drawings:—

Figure 1 is a view showing a number of blocks constructed according to my invention in use.

Figure 2 is a plan view of a number of blocks constructed according to my invention associated together so as to form a word or sign.

Figure 3 is a section of one construction of block secured to a concrete or other base.

Figure 4 is an underface view of the metallic portion of the block.

Figure 5 is a section of a modified construction.

Figure 6 is an underface view of the metallic portion of the block shown in Figure 5.

Figure 7 is a section of a modified construction of block.

Figure 8 is a view of a further modified construction.

In carrying my invention into effect I prefer to construct the elements 1 of cast or forged metal, such as aluminium, which will present a relatively rough surface and which is of a colour which will show up clearly in relation to most of the road surfacing materials at present used.

In the construction illustrated by the accompanying drawings each element 1 is provided upon its under surface with a number of downwardly projecting bosses or lugs 2 within each of which is embedded a bifurcated rivet or split pin 3 having its centre bent into an eye 14 and its ends 4 bent outwardly prior to the insertion of the element within the concrete or other base member 5 which is allowed to set around them and thereby retain the paving element firmly in position.

In the case of the metallic elements or plates being formed as castings, the eye portions 14 of the bifurcated rivets or split

pins are placed in the mould and the metal forming the plate and bosses flows around and through the eyes so that they are held very firmly.

6 Each of the metallic elements may be provided with holes 6 in the shape of letters or numbers, which holes can be conveniently formed when casting. These holes may be filled in with a suitable substance such 10 as a coloured cement 7 which may project above the surface of the surrounding metal and form a non-slipping surface and at the same time be readily seen.

15 If desired, instead of the metallic elements having holes in the shape of letters or numerals, they may be provided with holes arranged in any suitable manner such as is shown clearly in Figures 5 and 6 through which the cement or concrete 20 foundation may project at 8, and thus form a non-slipping surface.

In the construction shown in Figure 7, instead of the holes or openings in the metallic element being filled in with cement, concrete or the like, they are provided with 25 blocks 9 of material such as rubber which project from the surface and are prevented from becoming displaced by flanges 10 which engage with the under surfaces of 30 the metallic element.

In the construction illustrated by Figure 8 I have shown an indicating device in the form of an arrow. In this construction the arrow 11 is formed as a metallic plate and is 35 provided with downwardly projecting members each of which is secured within a lug upon the under surface of the metallic element and engages with the concrete or other foundation 12 in a similar manner to the 40 previously described constructions.

In order that the arrow may be rendered "non-skidding" it may be provided with 45 holes or openings 13 which may be filled in with coloured cement, blocks of rubber or the like, or through which the concrete or other foundation may project.

An indicator in the form of an arrow constructed according to my invention can be 50 readily observed by the drivers of vehicles and can be used in a variety of ways for the control of traffic. For instance, one or more arrows can be used in conjunction with a white line as shown clearly in Figure 1, the white line being also built up of a 55 number of blocks, whilst as shown also in Figure 1 my construction of blocks which include numerals or letters may be mounted in the road surface at suitable points for the control of traffic.

If required, the upper surface of the block 60 may be cast or otherwise formed with holes in the shape of letters as in the construction illustrated, or the said upper surface may be left plain or it may be provided with a number of holes or openings 65 into which the material of the road surface will project.

If required, instead of allowing the material of the road surface to project into the said holes or openings, pitch or other 70 material may be poured into the said letters or openings from above.

If required, blocks may be constructed 75 having the letters S T O P and such blocks can be used with any other plain or perforated blocks for a stop line such as is shown clearly in Figures 1 and 2.

The metallic elements forming my improved blocks may, if desired, be curved to conform to the shape of the road or 80 other surface as shown clearly in Figures 5, 6 and 7.

What I claim then is:—

1. A traffic sign element comprising a block formed by a cast metal plate having 85 integrally formed lugs upon one side, anchorage members cast in said lugs and having a plurality of prongs projecting therefrom, a moulded backing in which said anchorage members are embedded, said plate 90 having openings, and non-slipping blocks in said openings.

2. A traffic sign element comprising a block formed of a metal plate having lugs on one side, anchorage members secured in 95 said lugs and having a plurality of prongs projecting therefrom, a moulded backing in which the anchorage members are embedded, said plate having openings therein, and non-slipping material in said openings. 100

3. A traffic sign element, comprising a block formed of a metal plate having lugs on one face, anchorage members secured in said lugs, a moulded backing in which the anchorage members are embedded, said 105 plate having openings therein, and flanged non-slipping blocks anchored in said openings.

4. A traffic sign element comprising a block formed of a metal plate having lugs 110 on one face, anchorage members secured in said lugs, a moulded backing in which the anchorage members are embedded, said plate having openings therein, and non-slipping flanged resilient blocks anchored in said 115 openings.

In witness whereof I affix my signature.
THOMAS JAMES PRIESTMAN.
